UNITED STATES PATENT OFFICE.

WILLIAM B. PEIRCE, OF NORTH TONAWANDA, NEW YORK, ASSIGNOR TO BUFFALO BOLT COMPANY, OF NORTH TONAWANDA, NEW YORK, A CORPORATION OF NEW YORK.

COIL-HEATING FURNACE.

1,243,443.

Specification of Letters Patent. Patented Oct. 16, 1917.

Application filed June 23, 1914. Serial No. 846,744.

To all whom it may concern:

Be it known that I, WILLIAM B. PEIRCE, a citizen of the United States, and a resident of North Tonawanda, in the county of 5 Niagara and State of New York, have invented certain new and useful Improvements in Coil-Heating Furnaces, of which the following is a specification.

This invention concerns progressively 10 heating a continuous length of material while feeding it into, through and out of a furnace. It involves a method of handling the material, which, though useful for other purposes, is particularly adapted for furnaces and operations where the metal is 15 heated to a very high temperature, particularly where heated up to the softening point. Effective heating to such temperatures requires that the metal passing through 20 the furnace be kept freely exposed on all sides to a very high heat for a considerable time. To do this with the metal passing straight through the furnace would require either a very slow feed or a very long 25 furnace, whereas it is desirable to use a relatively small, compact furnace and to give the metal a desired high rate of feed into and out of the furnace combined with a relatively slow rate of progress through 30 the furnace.

For such purposes, it has been proposed to accomplish this by giving the metal a straight feed into and out of the furnace, the intermediate portions being wound 35 tightly around a revolving drum within the furnace. Such method involves extensive contact of the metal with the drum and prevents its free exposure and uniform heating on all sides. On the other hand, winding 40 the metal in large, open, freely suspended coils in accordance with my present method has not heretofore been attempted because of the difficulties resulting from the initial stiffness of the metal and the effect 45 of the heat in softening it.

My method, while capable of useful employment for operations permitting tight winding of the material on the drum, is of much greater importance and usefulness for 50 operations requiring free suspension and exposure of the metal for effective, uniform,

high temperature heating. It involves giving to the material fed into the furnace a predetermined initial shape and set in the curvature of a coil or helix of desired diameter and length suitable to the stiffness of the material and the size of the furnace. This material is wound into the furnace so that it hangs loosely from a suitable support and, though the material is more or less 60 flexible, the construction of the support is such as to permit the successive turn to assume and maintain a curvature and spacing roughly approximating the coil or helix shape originally given it. 65

By suitably predetermining the length of the interior support and the number of turns of the helix hanging thereon, the length of time required for travel of each turn through the furnace may be as long as 70 necessary. Hence, it is possible to maintain the required rate of output of heated material while using a relatively small, compact furnace.

Because of the effect of the heat upon the 75 coiled material in softening it, it is necessary to carefully control the rates of movement of the metal at the supply end and the exit end, so that it will be unwound from the exit end of the helix by the time it has 80 become softened to the proper degree and before it becomes too soft to maintain proper separation of the turns of the helix.

The material is uniformly heated because the amount of it which actually touches the 85 support is small and the point of contact is more or less shifting.

The material to be heated may be supplied in ready formed coils containing any desired length of the material, preferably the ordinary commercial coils obtainable from the rod mills. Such material already has an initial shape or set of approximately the curvature of the coil in which it is marketed and such curved shape or set may be utilized in the formation of the desired helix within the furnace, the method of transfer into the furnace operating to progressively open out the coils to the desired helical form. 95

The transfer of the material from the exterior coil to the interior helix may be effected, with or without change in the diameter,

eter of the turns, through an oblique opening into the furnace, and this opening need not be of much greater diameter than the thickness of the material.

5 My above described method for progressively heating coiled material may be used for any desired purpose but it is particularly applicable to the heating of iron until it is soft enough for forging operations. In 10 such case, it saves the necessity of straightening and cutting the coiled material into lengths, heating it in long furnaces and transferring it by hand to the automatic forging machine or other apparatus in 15 which it is to be used.

The specific means for transferring the exterior coiled material into the furnace and for giving the successive turns the desired helical form is shown herein as consisting 20 of an exterior rotor carrying an oblique opening through which the coiled material in helical form passes into the furnace, the rotary path of said opening being in operative relation to an external support for the 25 supply coil and an internal support for the helix which is formed therefrom. The longitudinal support within the furnace is preferably non-rotating and preferably comprises a conical mandrel portion of approxi- 30 mately the diameter of the helix to be formed and upon which the feed rotor lays, the material to be heated in helical relation, and a more or less horizontal extension of much smaller diameter along which the successive 35 turns of the helix progress in properly spaced relation while exposed on all sides to the heat of the furnace.

The fully heated material is shown as 40 being withdrawn endwise from the remote end of the helix. Other specifically different arrangements for accomplishing the formation, support, axial travel and unwinding of the helix are shown in my copending application, Serial No. 659,467, filed November 45 10th, 1911. The broader features of the method herein disclosed are broadly claimed in my co-pending application, Serial No. 74,330, filed January 26th, 1916.

My present apparatus and its generically 50 similar but specifically different method of operation will be more fully understood from the following detailed description in connection with the accompanying drawings, in which—

55 Figure 1 is a side view, partly in section on the line $x-y$, Fig. 2, showing a furnace and feed mechanism embodying my invention;

Fig. 2 is a plan view of the parts shown 60 in Fig. 1;

Figs. 3, 4, 5, 6, and 7, are detail views of portions thereof.

In the drawings, similar reference letters 65 denote corresponding parts in the several figures.

In the drawings, 2 represents a furnace whose walls are shown at 1, 1, constructed of heat resisting materials in the usual manner, and which may be heated by any of the means customarily used for this purpose. 70

In the drawings, it is shown as supported and strengthened by through-bolts, 49, 49, and stays, 44, 45, 46, 47, 47, 48.

The heating chamber within the furnace is of suitable dimension to provide for a 75 helix of desired number, diameter and separation of turns and for an orderly withdrawal of the heated material therefrom.

The means for forming and supporting the desired helix of the material to be heated within the furnace is preferably movably mounted with respect to the furnace upon a track 3. To this end, I provide a truck 4, mounted on wheels 5 carrying a massive standard 6. In the latter is rigidly secured 80 a forwardly extending hollow support 7 carrying the disk 8 upon which is mounted a conical mandrel 9 having an internal passage or chamber 10 continuously supplied with cooling water through horizontal pipes 90 11, 12 extending through the hollow support 7 and connecting with the interior of said mandrel through radial pipes 13, 14.

Extending forward from the uppermost portion of the annular mandrel 9 is a hanger 95 15 in suitable relation for receiving the successive helical turns of the material and for holding them freely suspended and exposed to the heat on all sides. As will be evident from Figs. 1, 3 and 4, the hanger comprises 100 a U-shaped pipe in communication with the interior 10 of the mandrel 9, for free circulation of the cooling water.

The circular interior of the mandrel is formed so as to support the lining of fire-brick adapted to protect the supporting disk 8 and water pipes 13, 14 from the heat within the furnace and at the same time to furnish reverberatory heating surface for the interior of the furnace. 105

Upon the support 7 is journaled the hollow shaft 16, for which I preferably provide roller bearings at the forward end 17. This shaft is adapted to be power-driven through gears 18, 19, 20 and 21, the latter being mounted upon power shaft 22 carrying fast and loose pulleys 23, 24, which may be operated by a shiftable belt or other source of power not shown. 110

The shaft 16 carries the rotary disk 25 120 which is formed or provided with a circular peripheral bearing resting upon the anti-friction rollers 29, which may be mounted either on truck 4 or on the foundation adjacent thereto.

As will be evident, the above described construction affords an ample interdependent support for the non-rotating mandrel structure above described as well as for the rotary member itself. 125 130

The rotor 25 has secured thereto by clamps 27, 27, an annular ring of fire brick 26 extending outward beyond but closely adjacent to the base of the mandrel 9.

5 The above described structure mounted on the truck 4 forms a removable circular wall adapted to close the circular aperture 28 so as to minimize escape of flame and heated gases during the operation of the 10 device. Obviously, the major portion of the closure consists of the stationary mandrel and fire-brick carried thereby, while the rotary annulus 26 supplies a closure for the annular space 28 around the mandrel.

15 The coiled material 32, 34, to be fed into the furnace is supported upon the rotor in any desired way as by shaft 30 carrying a spool or drum 31, which is rotated by winding of the material onto the mandrel.

20 An oblique opening for passage of the material to the mandrel within the furnace is provided by substituting a suitable shaped metal block 33 or 33^a in place of two of the 25 bricks 26. The blocks are shown in detail in Figs. 6 and 7 in two forms, one adapted for right hand and the other for left hand revolution as indicated by the arrows in those figures.

25 The feeder block is furnished with a flange 34 whereby it may be belted in position and it may be made hollow and water cooled if desired.

Opposite the uppermost portion of the 30 mandrel is arranged a correspondingly shaped coöperating clamping block 36 which is made hollow and supplied with water through the supports 37, 37, which are secured to the lever 38, pivoted at 39, 35 and furnished with a weight, 42, and operated by a handle, 40, pivoted at 41, and supplied with a balancing weight, 43.

40 The furnace is shown as supplied with an opening, 54, for the withdrawal of the material after heating.

45 This opening, 54, is furnished with a door, 53, supported by a link, 52, from the arms, 51, 51, secured upon the shaft, 50, mounted in bearings upon the furnace frame, and also furnished with weights 58, 58, carried upon the arms, 57, 57, to balance the door, 53.

50 This door is raised and lowered by means of the lever, 55, and handle, 56.

55 The operation of my device is as follows:

A coil of material having been placed upon the support, 30, an end thereof is passed through the slot, 35 or 35^a, of one of the feeders, 33 or 33^a, secured upon the disk, 25.

60 The end of the material is now passed beneath the clamp, 36, which is lowered to grip it against the conical face of the mandrel, 9.

65 Power now being applied, the shaft, 16,

carrying the disk, 25, and feeder, 33, is now revolved away from the clamp, 36, and by its revolution, the feeder travels around the annular entrance, 28, and slides along the coiled material, which, rotating upon its support, 30, is fed through the inclined slot, 35 or 35^a, of the feeder, on to the conical surface of 9, and the successive coils of material thus laid upon the conical surface of 9, push each other downward upon this surface and into the furnace chamber where they hang upon the hanger, 15, and are heated.

70 They are readily drawn out of the furnace through the opening, 54, slipping successively off from the hanger, 15.

75 Successful operation of the apparatus in the manner above described depends upon several coöperating factors of which the following may be noted:

80 The angle and length of the oblique opening through the rotating feeder block 33 and its relative position with respect to the pitch of the mandrel upon which it winds the material, as well as the shape and degree of pressure of the clamp 36 are all designed with reference to the stiffness and natural curvature or set of the coiled material so as to impart the required helical shape or set to the material deposited upon the mandrel. The mandrel itself is formed with a decreasing pitch so that as the successive turns of the helix are relieved of the 85 presser foot, they pass off of the mandrel and on to the hanger in an orderly manner.

90 The hanger has for a considerable portion of its length an inclination corresponding to the downward inclination of the uppermost part of the mandrel thus assisting a forward sliding movement of the turns of the helix under the influence of gravity. As the turns slide down the hanger and become more or less softened, their points of contact with the hanger are shifted more or less so that the heating is substantially uniform. The free end of the hanger is curved 95 upwardly so as to furnish a stop against the natural sliding of the coils by gravity thereby retaining them until positively withdrawn through the exit opening 54. Such 100 withdrawal should be substantially continuous so that a fully heated coil will not be permitted to remain long enough to have a succeeding coil come into contact with it 105 after being softened to the welding point.

110 The successive positions of the coils of the helix are indicated with more or less accuracy at 32°, 32^b, 32^c, etc., but it will be understood that the presser foot and mandrel prevent decrease of periphery of the 115 turns of the coils after they are once laid down, and if the successive turns on the mandrel sometimes appear to be of different diameters, it is because of slight variations in operation of the feeding mechanism.

130

While I have herein shown and described with considerable particularity a desirable embodiment of my invention, the invention is nevertheless a broad one and it will be obvious, that various changes, omissions, additions and modifications may be made without departure from the spirit thereof, and certain of the claims herein are broad enough to cover the apparatus shown in my copending applications Serial Nos. 659,467 and 74,330. While the method herein disclosed is specifically different from the specific method disclosed in my said copending application No. 74330, they have certain broad features in common, and various of the broader claims of said application 74,330 are broad enough to cover the method disclosed in this application.

What I claim as new and desire to secure by Letters Patent, is:—

- 20 1. A furnace having an annular entrance for ingress of the material to be heated, and having a revolubly mounted feeder adjacent thereto.
- 25 2. A furnace having an annular entrance for ingress of the material to be heated, in combination with a revolubly mounted feeder arranged to pass before successive portions of said annular entrance in its revolution.
- 30 3. A furnace having an annular entrance for ingress of the material to be heated, in combination with a revolubly mounted feeder adapted to pass in its revolution before said entrance with means for moving said feeder in a circular path.
- 35 4. A furnace having an annular entrance for ingress of the material to be heated, in combination with a revolubly mounted feeding member whereby material is fed through successive portions of the annular entrance.
- 40 5. A furnace having an annular entrance for ingress of the material to be heated, in combination with a revolubly mounted feeding member adjacent to said entrance, with means for moving said feeder in a circular path.
- 45 6. A furnace having an annular entrance for ingress of the material to be heated, said entrance being furnished with a sloping surface of substantially the form of a conical frustum, and having a revolubly mounted feeding member adjacent to said entrance whereby it is adapted to deliver the material upon or around said surface.
- 50 7. A furnace having an annular entrance for ingress of the material to be heated, said entrance being formed interiorly by a circular member furnished with an exterior central support.
- 55 8. A furnace having an annular entrance for ingress of the material to be heated, said entrance being formed interiorly by a circular member furnished with an exterior

central support and carrying a supporting member projecting into said furnace.

9. A furnace having an annular entrance for ingress of the material to be heated, said entrance being formed interiorly by a circular member furnished with an exterior central support and having a hollow rim, with means for supplying circulation of water thereto.

10. A furnace having an annular entrance for ingress of the material to be heated, a support within the furnace for supporting the material in the direction of the axis of said entrance, and a passage for removal of the material from the furnace placed substantially in the vertical plane of said axis, whereby the material may be introduced and heated while supported in coiled form, and withdrawn nearly straight from said furnace.

11. A furnace having a circular entrance, with a circular member of less diamter partially closing it and leaving an annular opening, said member being supported so as to be movable axially of said entrance, with a rotating feeder supported thereon and with means for rotating said feeder, all mounted so as to be movable axially of said entrance.

12. A furnace having an interior coil supporting member, and the wall of the furnace having a feed aperture therethrough through which the material may be fed to said coil supporting member, and said aperture leading obliquely into the furnace in a position and direction corresponding approximately to the periphery of the coils to be supported by said interior supporting member.

13. A furnace provided with suitable entrance and exit openings for the material to be heated, in combination with a feed mechanism adapted and arranged with respect to the entrance opening so as to feed into the furnace, material initially shaped and set in a suitable curvature so as to cause said material to progressively form an axially advancing coil or helix within the furnace between the entrance and exit openings thereof.

14. A furnace, a horizontal coil supporting member within said furnace, said coil supporting member being of a diameter smaller than the interior diameter of the coil to be supported thereby so that the coil will hang loosely therefrom and expose substantially all portions of the coil uniformly to the heat of the furnace and means for progressively depositing upon said supporting member, material ready shaped or set in the form of an open coil or helix.

15. A furnace having an annular entrance for ingress of the material to be heated, a support for the material within the furnace and mounted upon the part encircled by said

entrance, and projecting in the direction of the axis of said entrance and an exit for the withdrawal of the material in the opposite furnace wall, whereby the material may be introduced, heated while supported in coil form, and withdrawn endwise from the free end of said support and out of said furnace.

16. A furnace having a circular opening in one wall thereof, a closure for said opening, a support upon the exterior of said closure for supporting material in coil form, a support upon the inner surface of said closure for supporting material in coil form and means for transferring material from said first mentioned support to said second mentioned support through an annular entrance opening between the periphery of said closure and the edge of said opening.

17. A furnace having a circular opening in one wall thereof, a support outside of said furnace and movable toward and from said opening, a closure carried by said support, and having a part spaced from said opening to leave an annular space, means on said support for holding material in coil form and power means also carried by said support for advancing the material through said annular space.

18. A furnace having a circular entrance opening, a truck adjacent to said opening and movable toward and from the same, a circular part carried by said truck for insertion within said opening to leave an annular space encircling said part, a support within said furnace and carried by said part for sustaining material in coil form, means for supporting the material in coil form upon said truck outside of said furnace and means for delivering material to said first mentioned support from said second mentioned support through said annular space.

19. A furnace having a circular opening, a part disposed within said opening and having a surface spaced from said opening to leave an annular entrance for ingress of the material to be heated, a support projecting from said part within the furnace in the direction of the axis to said entrance, and means for delivering material through said annular entrance in coil form to said support, said furnace having an outlet opening in the wall thereof opposite to said support and from which the material may be drawn endwise off the free end of said support.

20. A furnace having a support projecting inwardly from one wall thereof, for sustaining material in coil form with the axis of the coil substantially horizontal, and means for delivering material to said support in coil form, said furnace having an outlet opening in the wall thereof opposite to said support and from which the material may be drawn endwise off the free end of said support.

21. A furnace having a circular opening, a non-rotatable part disposed within said opening and having a conical surface spaced from said opening to leave an annular entrance for ingress of the material to be heated, a support projecting from said part within the furnace in the direction of the axis to said entrance, a feed device movable around said part for delivering material through said annular entrance in coil form to said support, and a pressure device for preventing rotation of the coil material on said support.

22. A furnace having a circular opening, a conical closure therefor, a support projecting inwardly and downwardly from the inner surface at the upper edge thereof, the inner end of said support being turned upwardly, and means for delivering material around said closure to said support in coil form with the axis of the coil substantially horizontal, and below said support, said furnace having an outlet opening in the wall thereof opposite to said support and from which the material may be drawn endwise off the free end of the support.

23. A furnace having a circular opening, in one wall thereof, a conical closure of decreasing pitch for said opening and spaced from said opening to leave an annular passage, a support for coil material at the upper edge of the inner surface of said closure and projecting inwardly in line with the conical surface of the closure, and a rotatable member including a feed device covering a portion of the outer end of said annular passage for delivering coil material to said passage and a flange covering the balance of the outer end of said passage.

24. A furnace of the class described, formed with a circular entrance opening in a wall thereof and with an exit opening in the opposite wall, an annular mandrel, a coil support extending forwardly from said mandrel, and means external to the furnace for supporting said mandrel within said circular opening so as to form an annular passage for axial advance of successive coils of the material to be heated, in combination with a rotor coaxial with said mandrel, formed or provided with an annular surface adapted to form a rotary annular closure closely adjacent said annular passage, and with an oblique opening in operative relation for endwise passage of the material in coil form into said annular space and for laying successive coils thereof on said mandrel.

25. A furnace of the class described, formed with a circular entrance opening in a wall thereof and with an exit opening in the opposite wall, an annular mandrel, a refractory wall supported within said mandrel, a coil support extending forwardly from said mandrel and means for support-

10 ing said mandrel within said circular opening so as to form an annular passage for axial advance of successive coils of the material to be heated, and a member yieldingly
15 pressed toward said mandrel so as to yieldingly clamp a portion of each successive coil of the material deposited on said mandrel, in combination with a rotor formed or provided with an annular surface adapted to form a rotary annular closure closely adjacent said annular passage and also formed or provided with an opening in operative relation for endwise passage of the material in coil form into said annular space and for laying successive coils thereof on said mandrel.

26. A furnace of the class described, formed with a circular entrance opening in a wall thereof and with an exit opening in the opposite wall, an annular mandrel, a coil support extending forwardly from said mandrel, a stationary member for supporting said mandrel within said circular opening so as to form an annular passage for the axial advance of successive coils of the material to be heated, and a clamping member co-operating with said mandrel to yieldingly clamp a portion of each successive coil of the material deposited on said mandrel, in combination with a rotor journaled upon and coaxial with the stationary mandrel support, said rotor being formed or provided with an annular surface adapted to form a rotary annular closure closely adjacent said annular passage and also formed or provided with an oblique opening in operative relation for endwise passage of the material in coil form into said annular space and for laying successive coils thereof on said mandrel, and also formed or provided with a peripheral bearing surface; together with suitable roller supports engaging said peripheral bearing surface on opposite sides of its vertical axial plane, thereby supporting and centering said rotor and through it the mandrel support on which it is journaled.

27. A furnace of the class described, formed with a circular entrance opening in a wall thereof and with an exit opening in the opposite wall, an annular mandrel having its periphery in the form of a cone-like frustum, a coil support comprising a water cooled pipe loop extending forwardly 50 from said mandrel with a downward inclination for the major portion of its length and an upward inclination toward the free end thereof, means external to the furnace for supporting said mandrel within said 55 circular opening so as to form an annular passage for axial advance of successive coils of the material to be heated, and a clamping member coöperating with said mandrel to engage successive coils of the material as 60 they are progressively deposited on said 65

mandrel, in combination with a rotor formed or provided with an annular surface adapted to form a rotary annular closure closely adjacent said annular passage and also formed or provided with an oblique opening in operative relation for endwise passage of the material in coil form into said annular space and for laying successive coils thereof on said mandrel. 70

28. A furnace of the class described, 75
formed with a circular entrance opening in
a wall thereof and with an exit opening in
the opposite wall, an annular mandrel hav-
ing its periphery in the form of a cone-like
frustum, a refractory wall supported within 80
said mandrel, a coil support extending for-
wardly from said mandrel with a downward
inclination for the major portion of its
length and an upward inclination toward
the free end thereof, means external to the 85
furnace for supporting said mandrel within
said circular opening so as to form an an-
nular passage for axial advance of suc-
cessive coils of the material to be heated, a
presser foot movably mounted in the wall 90
of said furnace and yieldingly pressed to-
ward said mandrel to yieldingly engage suc-
cessive coils of the material as they are pro-
gressively deposited on said mandrel, in 95
combination with a rotor formed or pro-
vided with an annular surface adapted to
form a rotary annular closure closely adjac-
ent said annular passage, and also formed
or provided with an oblique opening in op-
erative relation for endwise passage of the 100
material in coil form into said annular space
and for laying successive coils thereof on
said mandrel.

29. A furnace of the class described, formed with a circular entrance opening in a wall thereof and with an exit opening in the opposite wall, an annular mandrel having its periphery in the form of a cone-like frustum, a refractory wall supported within said mandrel, a coil support extending forwardly from said mandrel with a downward inclination for the major portion of its length and an upward inclination toward the free end thereof, a stationary shaft rigidly secured at its rear end for non-rotatably supporting said mandrel within said circular opening so as to form an annular passage for axial advance of successive coils of the material to be heated, a presser foot movably mounted in the wall of said furnace and yieldingly pressed toward said mandrel and adapted to yieldingly engage successive coils of the material as they are progressively deposited on said mandrel, in combination with a rotor rotatably mounted on the non-rotatable mandrel shaft, and itself peripherally supported by anti-friction rollers, said rotor being formed or provided with an annular surface adapted to form a rotary annular closure closely ad-

jacent said annular passage and also formed or provided with an oblique opening in operative relation for endwise passage of the material in coil form into said annular space and for laying successive coils thereof on said mandrel.

Signed at North Tonawanda, in the

county of Niagara and State of New York,
this thirteenth day of June, A. D. 1914.
